UNITED STATES PATENT OFFICE

ROBERT W. FISHER, OF CHICAGO, ILLINOIS, ASSIGNOR TO PETER RIESS, OF CHICAGO, ILLINOIS

LUMINOUS SIGN

Application filed August 27, 1928. Serial No. 302,243.

This invention relates to luminous signs and more particularly to a sign construction which will simulate in appearance the class of signs known as vacuum tube or neon signs.

5 It is an object of my invention to provide a sign having a panel piece with character formations through which light may readily pass, preferably in the form of slots, and to place over these character formations or slots 10 similarly shaped transparent characters which project outwardly from the surface of the panel in raised relation thereto.

Another object of the invention is to form the transparent glass characters from separate units of glass rods which seat into the slots in the panel piece.

Another object is to provide a coloring means for the glass characters which will avoid the difficulties encountered when the 20 coloring material is incorporated in the glass in the mould, and

Another object is to provide a coloring means for the glass characters which will produce a beautiful and artistic effect closely 25 simulating a vacuum tube sign.

Other objects of the invention will appear as the description proceeds.

Referring to the drawings:

Fig. 1 is a front elevation of my improved 30 sign;

Fig. 2 is a section taken on the line 2—2 of Fig. 1;

Fig. 3 is a section taken on the line 3—3 of Fig. 1;

35 Fig. 4 illustrates the slotted character formation in the panel piece;

Fig. 5 shows a character positioned over the slot in the panel piece; and

Fig. 6 is a detail view of a method of securing the character in place.

My improved sign comprises a housing having a top 1, back 2, sides 2', and a bottom 3, with an opening 4 closed by a slide 6 by means of which access is had to the interior 45 of the housing. The top 1 and bottom 3 are provided with air vents 7, one of which is illustrated in the top 1 in Fig. 3.

The front of the housing is closed by a panel piece 8 surrounded by a frame 9' which 50 is secured to the panel piece and to the hous-

ing by means of the screws 9 which pass through the U-shaped portions 10 of the top, bottom and sides of the housing. The source of illumination may be a battery of electric lights 11 supported in a bracket 12 and having leads 13 to a source of current.

55 In the panel piece 1, I provide character formations through which light may pass and over the character formations are transparent characters projecting outwardly from the plane of the panel piece. The character formations may be merely transparent areas in the panel piece spanned by raised transparent characters of any desired cross section, but in

actual practice, I find it most convenient and economical to provide the panel piece with 60 slots 14 having the formation of the desired character or letter and place over the slots similarly shaped rods of glass 15 secured in

place by wires 16 passing around the rods through holes 17 in the panel piece 8 and 65 twisted at the rear of the panel piece, as shown more particularly in Figs. 4 to 6. The rod extends slightly beyond the ends of the slots and its diameter is slightly greater than the

width of the slots so that the rod completely 70 covers the slots preventing any light from passing around between the edges of the slots and sides of the rods. The convex surface of

the rods seating into the slots also aids in 75 establishing an effective light seal. The numeral 17' indicates ornamental rods which may be disposed as desired.

80 While I have designated the characters as being transparent, it is to be understood that this term is intended to include characters, whether colored or frosted, through which the light may pass from the source at the opposite side of the panel piece.

85 I have found it highly desirable to associate coloring matter with the characters to produce varied and artistic effects and to closely simulate the more expensive vacuum tube signs. One method would be to incorporate the coloring matter in the glass itself.

90 But this is not satisfactory when the glass must be made into rods and bent into the desired form because the melting point of the glass is raised, making it difficult to work with and adding to the expense of forming 95 100

the characters. I have found that by coating the rods with transparent colored paint, this difficulty is avoided and, in addition, a superior effect is obtained, as the characters possess a brightness and sheen both when illuminated and not illuminated that they do not have when made of conventional colored glass. While I have shown only solid glass rods it will be understood that my invention is not limited to solid glass rods as hollow glass rods commonly referred to as glass tubing may also be used effectively.

I prefer to use a transparent glass paint known as aluminated paint as this paint produces very effective results. However, any other kind of transparent or phosphorescent paint may be used if desired. The paint is most conveniently applied to the surface of the rods but, if desired, when tubing is being used, the coating of paint may be applied to the inner surface of the tube and the tube then sealed, which will prevent deterioration of the paint due to exposure to the elements.

My improved sign not only rivals the vacuum tube or neon signs in effectiveness and appearance, but has several advantages not found in the vacuum tube type of sign. The vacuum tube signs are quite expensive because the characters must be formed from a continuous tube, difficult to form. The necessary electrical equipment also adds to the expense of the sign. In the sign herein disclosed, the letters are formed from separate pieces of unconnected rods and may therefore be cheaply made. If any portion of vacuum tube lettering is broken, the whole must be replaced at the expense of considerable time and money whereas the individual letters or characters in the present invention are not only cheap but they can be replaced immediately and without the use of skilled labor.

The vacuum tube sign is restricted to comparatively few colors, whereas any desired color can be used in my improved sign. Also, my sign, due to the brilliancy, sheen and gloss of the transparent colored paint on the tubing, is an effective sign in daylight whereas the colorless characters of the vacuum tube signs are not easily discernible and are quite ineffective as a daylight sign.

Having thus described my invention, what I wish to secure by Letters Patent of the United States is:

1. In a luminous sign, a panel piece of relatively opaque material having character formations through which light may pass, and similarly shaped rods of material through which light will pass forming characters fitted over and covering said character formations, said rods being so arranged as to permit substantially no light to be emitted through said character formations except that which passes through said rods.

2. In a luminous sign, a panel piece of rela-

tively opaque material having character formations through which light may pass, and similarly shaped separate units of transparent glass rods fitted over and substantially covering said character formations so as to prevent light from filtering around said units. 70

3. In a luminous sign, a panel piece having slotted character formations therein and similarly shaped characters of transparent glass rods held against said panel piece and substantially covering said slotted character formations. 75

4. In a luminous sign, a panel piece having slots cut therein in the form of the desired characters, and characters comprising separate units of glass rods of greater diameter than the width of said slots secured against said panel piece and substantially covering said slots to cause substantially all of the 85 light to pass through said glass rods. 80

5. In a luminous sign, a panel piece of relatively opaque material having character formations through which light may pass, and similarly shaped transparent characters 90 coated with colored transparent paint projecting outwardly from the surface of said panel piece and substantially covering said character formations to cause substantially all of the light emitted by said sign to pass 95 through said transparent characters.

6. In a luminous sign, a panel piece having slotted character formations therein and similarly shaped characters of transparent glass rods coated with colored transparent 100 paint held against said panel piece and substantially covering said slotted character formations.

7. In a luminous sign, a panel piece having slots cut therein in the form of the desired characters, and characters comprising separate units of transparent glass rods of greater diameter than the width of said slots secured against said panel piece and covering said 105 slots, said glass rods being coated with colored 110 transparent paint.

8. In a luminous sign, a panel piece of relatively opaque material, character formations in said opaque material through which light may pass, characters of substantially the same shape as said character formations adapted to be placed over said character formations to cause said characters to be illuminated substantially uniformly throughout the entire extent of said characters, said characters being formed of a material which will permit rays of light to pass therethrough, illuminating means on one side of said opaque panel, and means for preventing light emitted by said illuminating means from being visible from the other side of said panel except through said character. 115 120

9. In a luminous sign, a panel piece having slotted character formations therein and similarly shaped characters of transparent 130

colored glass held against said panel piece and substantially covering said slotted character formations.

In testimony whereof I have signed my name to this specification on this 23d day of August, A. D. 1928.

ROBERT W. FISHER.
